UNITED STATES PATENT OFFICE.

HOWARD L. FISCHER, OF ST. PAUL, MINNESOTA, ASSIGNOR TO BROWN & BIGELOW, OF ST. PAUL, MINNESOTA, A CORPORATION OF MINNESOTA.

PENCIL.

1,370,420.

Specification of Letters Patent. Patented Mar. 1, 1921.

Application filed June 24, 1920. Serial No. 391,409.

To all whom it may concern:

Be it known that I, HOWARD L. FISCHER, a citizen of the United States of America, residing at St. Paul, county of Ramsey, and 5 State of Minnesota, have invented certain new and useful Improvements in Pencils, of which the following is a specification.

My invention relates to pencils, the primary object of which is to provide a pencil 10 having a simple construction and particularly adapted to use a thin marking lead. My pencil is composed of only a few parts, which are simple to manufacture, and easily assembled for use.

15 The invention further provides means for readily determining the length of the unused marking lead in the pencil at any time so that the user can tell just how much unused lead remains in the pencil without separating the mechanism which propels the marking lead and without taking the same apart. This feature of the invention is important in the use of the pencil, as it gives the advantage of knowing how much marking 20 lead remains concealed in the pencil without exposing the same.

A further object of the invention is in 25 means providing a spring tension between the operating parts to take up any wear and 30 to prevent the removable portion of the operating mechanism from sliding out of the pencil barrel but allowing a portion of the same to be withdrawn from the barrel when it is desired to know how much marking 35 lead remains therein.

40 A feature of the invention is in providing a tubular longitudinally slotted operating member for the propelling mechanism which is provided with means for containing the propeller or lead driver to hold it freely slideable longitudinally therein, but against removal from the same, so that when the tubular operating member is withdrawn from the barrel the lead driver is removed 45 with the same. This construction provides means for preventing the tubular operating member from being entirely withdrawn from the barrel without the lead driving member. The lead driving member forms 50 a stop which tends to yieldably hold the tubular member in the pencil barrel.

It is also an object of the invention to provide a releasing means for the lead driver of the pencil to protect the projecting portion of the marking lead against a sharp

blow in the direction of the length. This releasing means allows the marking lead to move back into the barrel and also causes the driver to be picked up or engaged by the threads of the propelling means in any 60 position in the pencil without damage to the operating parts of the same.

In the drawings forming part of this specification:

Figure 1 is a side elevation partly in section 65 of my pencil.

Fig. 2 is a side elevation partly in section showing a part of the operating means withdrawn from the barrel.

Fig. 3 is a longitudinal sectional view of 70 the pencil.

Fig. 4 illustrates in perspective the tubular operating member of the propelling means with the lead driving member removed from the pencil.

Fig. 5 is a section on the line 5—5 of 75 Fig. 3.

Fig. 6 is a perspective view of the lead driver and socket.

The drawing illustrates the pencil barrel 80 10, which is made of thin tubular material adapted to inclose the lead propelling means B.

The lead propelling means is composed 85 of a tubular threaded member 11 the rear end 12 of which is not threaded, but is expanded to form an enlarged end which frictionally engages the inner wall of the rear end of the barrel 10 to hold the threaded member 11 rigidly against rotary or longitudinal movement in the barrel. The forward edge 13 of the threaded member 11 engages against the inner surface of the conical end 14 of pencil barrel 10. The edge 12' of the rear enlarged end 12 is flush 90 with the rear edge 15 of the open end of the barrel 10 when the threaded member is inserted in the barrel. It is obvious that the enlarged end 12 of the threaded member can be secured in the barrel by soldering in 100 addition to the frictional means or otherwise fastened rigidly therein.

The operating mechanism B is provided 105 with a tubular driving member 16 having a longitudinally extending open slot 17 through which the thread engaging end of the lead driving member 18 is adapted to project so that the notches or threads 19 formed in the driver 18 can engage the threads 20 of the member 11. An operating head 21 110

is secured to the rear end of the member 16. The forward end of the slot 17 is closed by the lip or shoulder 22, while the collar 23 on the forward end of the head 21 forms a 5 stop at the rear end of the slot 17. The lead driver 18 is held against disengagement in and from the tubular member 16 between the shoulder 22 and the collar 23. In this 10 manner the lead driver is held against disengagement from the member 16 after it has been assembled so as to prevent separation of these parts.

The lead driver 18 is formed with a 15 spring tongue 24 projecting from the rear end, which causes the threads or notches 19 of the same to engage with the inner surface of the threads 20 under spring tension, while a lead holding finger 25 projects from the forward end of the driver 18. The finger 25 carries a lead receiving socket 26 on its outer free end, which is adapted to receive the marking lead 27 to hold the same in writing and operating position in the pencil. The finger 25 can be either of a 20 spring or rigid nature so as to assist in holding the notches 19 into engagement with the threads 20. The spring finger 24 forms a frictional engagement between the member 16, driver 18 and the threaded 25 tube 11 to prevent free longitudinal movement of the member 16 in the pencil. However, the member 16 can be withdrawn until the shoulder 22 engages against the forward edge of the member 18 as is illustrated in Fig. 2. When the forward end of the lead is at the end of the conical end 14 and the member 16 is thus withdrawn the distance between the rear edge 15 and the inner surface 28 of the operating 30 head 21 indicates the length of unused lead still remaining in the pencil; thus Fig. 2 illustrates, by the distance between the arrows, the unused portion of lead in the pencil. This figure shows convenient means 35 for indicating to the user of the pencil how much lead still remains for use.

When the marking lead 27 has been used up in the operation of the pencil, a new marking lead can be inserted in the socket 40 26 by unscrewing the driver 18 from the threaded member 11. This is accomplished by rotating the end 21 allowing the member 16 to project out of the pencil as the driver is unscrewed. In the operation of the pencil if an unused portion of the marking lead 45 is projected out of the marking end of the pencil farther than is desired for use it can be withdrawn into the pencil barrel by operating the head 21 in the reverse direction to the forward propelling operation. The 50 rotary movement of the operating head 21 rotates the member 16 in the threaded member 11 to move the driving member over the threads 20 to propel the same in either direction. When the member 16 is removed

from the pencil barrel as illustrated in Fig. 4, the lead driving member 18 is held in forward position in the slot 17, while the stub of the old marking lead is removed from the socket 26 and a new marking lead inserted in the same. 70

In the assembling of my pencil the tubular shell-like barrel 10 received the threaded member 11 by the frictional engagement of the enlarged end 12 to hold the threaded member rigid in the barrel. The lead driver or propeller 18 is inserted in the tubular member 16 with the thread engaging notches projecting through the slot 17 and the shoulder 22 is then bent to close the forward end of the slot. The propeller is then ready to receive the marking lead in the socket 26 and to be inserted into the threaded member 11 by rotating the operating head 21. The simplicity of construction 80 gives a pencil practical for use and economical to manufacture.

The lead driving member 18 is resiliently held by the spring finger 24 against threads 20 and should the pencil be dropped so that 90 the portion of the marking lead 27 projecting from the same is struck a sharp endwise blow the spring finger 24 will allow the threads or notches 19 to disengage from the threads 20 and ride backward longitudinally over the same, to release the marking lead in a backward direction. This protects the marking lead from a sharp blow, caused by dropping the same on the point or otherwise striking the point of the marking lead 10 with sufficient force to cause the driver 18 to move backward. The spring finger 24 also forms resilient means to cause the driving member 18 to be picked up by the threads after it has been forced backward 10 to propel it in either direction in the pencil. This construction prevents damage to the marking lead when the pencil is dropped on the point and also protects the driving member together with the threads 11 and the propelling mechanism. This feature is an important part of my invention.

In accordance with the patent statutes I have described the principles of operation of my invention, together with the apparatus which I now consider to represent the best embodiment thereof, but I desire to have it understood that the construction shown is only illustrative and that the invention can be carried out by other means 12 and applied to uses other than those above set forth within the scope of the following claims:

1. A pencil having a barrel, a lead propelling means, comprising a tubular threaded member rigidly held therein, a rotatable longitudinally slotted member having an operating head on one end and a spring driving member held slidable therein adapted to form a frictional engagement between said 13

rotatable member and said threaded member to hold said parts against free movement in said pencil.

2. A pencil having a barrel, a threaded member, an unthreaded portion formed on said threaded member adapted to frictionally engage said barrel to rigidly hold said threaded member, an operating member removably held in said threaded member and a resilient lead driving member adapted to 10 form a frictional engagement between said operating member and said threaded member.

3. A pencil comprising a barrel, a threaded member fixed in said barrel, a tubular operating member rotatably and removably held in said barrel, a longitudinal slot extending in said operating member, a lead driving member adapted to extend through 20 said slot, means for holding said lead driving member in contact with said threaded member under spring tension and a shoulder formed on the forward end of said operating member adapted to hold said lead driving member against disengagement from 25 said operating member.

4. A pencil, including a threaded member, a lead driving member adapted to resiliently engage the threads of said threaded member; the connection between the threads and the driving member being such that a sharp blow against the writing lead in said pencil will cause said driver to slip over said threads, releasing the marking lead in a 35 backward direction into said pencil to protect the marking lead in said pencil.

5. A pencil, including a threaded lead propelling means comprising, a resilient thread engaging means forming the lead carrier of 40 said propelling means, the connection between said resilient engaging means and the threads of the propelling means being such as to allow the resilient means to ride over the threads of the propelling means when 45 the marking lead is struck a sharp blow.

6. A pencil, including a barrel, formed of thin tubing, a conical forward end, a tubular threaded member rigidly held in said barrel with the forward end engaging said 50 conical end, a removable tubular member having an engaging end projecting out of the rear end of said pencil, a longitudinal slot formed in said removable member, a lead driving member adapted to operate in 55 said slot, a spring tongue formed on the rear end of said lead driver, threads formed in said lead driving member and a spring lead holding finger projecting from the forward end of said driver.

60 7. A pencil, comprising a lead propelling means including a removable operating member, a resilient lead driving member adapted to form spring engaging means between said operating member and the parts 65 associated therewith and means for holding

said tubular member and lead driving member collectively removable with the marking lead from said pencil.

8. A pencil, comprising a lead propelling means, a lead driving member adapted to 70 resiliently engage said propelling means, a removable tubular member adapted to operate said driving member and means for holding said tubular member and lead driving member collectively removable with the marking 75 lead from said pencil.

9. A pencil lead propelling means including a threaded member, a spring lead propelling member adapted to engage said 80 threaded member under spring tension, and releasable from said threaded member to move longitudinally when more than writing pressure is exerted against the lead.

10. A pencil having a screw lead propelling means and means adapted to slip and 85 hold the lead concealed in said pencil by a non-rotary longitudinal movement when extreme pressure is exerted against the lead.

11. A pencil having a barrel, an operating portion withdrawable to indicate the length 90 of unused lead remaining in said barrel and a lead carrier having spring means adapted to form frictional means to prevent free sliding of said withdrawable portion.

12. A pencil including a barrel, a lead- 95 propelling means comprising a removable operating member, a lead driving member adapted to form a stop to limit the withdrawing of said operating member from said barrel and spring means associated with 100 said lead driving member adapted to form frictional holding means between said operating member and said propelling means.

13. In a pencil adapted to advance the 105 lead by a threading action, and wherein the lead carrier is one of the threaded elements and adapted to normally engage the complementary threads of a pencil case element, means coöperating with the carrier to permit shift of the carrier in the direction of 110 length of the pencil to vary the thread engagement by pressure against the projected lead.

14. In a pencil adapted to advance the 115 lead by a threading action, and wherein the lead carrier is one of the threaded elements and adapted to normally engage the complementary threads of a pencil case element, means coöperating with the carrier to permit yielding of the latter to change the 120 threaded relation independent of normal threading movement and in the presence of pressure applied against the lead.

15. In a pencil having a lead carrier shift- 125 able to expose the lead at the writing point at will, means rendered active solely by the application of pressure against the projecting lead for restoring and retaining the lead to its housed position.

16. In a pencil having a lead carrier shift- 130.

able to expose the lead at the writing point at will, means rendered active by the application of pressure exerted on the exposed lead for restoring and retaining the lead to 5 its housed position.

17. In a pencil having a lead carrier shift-
able to expose the lead at the writing point
at will by a threading movement, means for
restoring and retaining the lead to its
10 housed position by movement of the carrier
independent of the threading movement.

18. In a pencil having a lead carrier shift-
able to expose the lead at the writing point,
said lead carrier being adapted to move
15 alone to house the lead when excess pres-
sure is exerted against the projected end of
the lead.

19. A lead propelling means for a me-
chanical pencil comprising a lead carrier,
20 compensating means associated with said
carrier to take up the wear in said lead
propelling means, and permitting said car-
rier to shift to house the marking lead when
pressure is exerted against the same.

25 20. A mechanical pencil including a lead
carrier formed from a flat thin piece of
material, resilient ends extending longitudi-

nally from the ends of said carrier and
means for operating said carrier.

21. A lead carrier for a mechanical pencil 30
including a flat thin body portion and resili-
ent means projecting longitudinally from
the end thereof.

22. A lead carrier for a mechanical pencil
including a body portion, resilient means 35
extending from said body portion and lead
retaining means on one end thereof, said
carrier being adapted to be associated with
an operating mechanism in a manner to pro-
pel it in either direction and said resilient 40
means of said carrier allowing it to be re-
leased and slipped backward independent
of the operating means.

23. In a pencil, a casing, a threaded mem-
ber, an operating member and compensat- 45
ing means adapted to form a uniform fric-
tion between said threaded member and said
operating member and to form the lead en-
gaging member of said pencil, the resilient
portion of said compensating means extend- 50
ing longitudinally from the body portion
thereof.

HOWARD L. FISCHER.
